UNITED STATES PATENT OFFICE

ALEXANDER JAMESON, OF INDIANAPOLIS, INDIANA.

CASTING APPARATUS.

950,106.

Specification of Letters Patent. Patented Feb. 22, 1910.

Application filed March 4, 1908. Serial No. 419,080.

To all whom it may concern:

Be it known that I, ALEXANDER JAMESON, a citizen of the United States, residing at Indianapolis, in the county of Marion and 5 State of Indiana, have invented certain new and useful Improvements in Casting Apparatus, of which the following is a specification.

In the casting of very small articles from 10 gold and other similar metals, such for instance as metal inlays for teeth, jewelry, etc., difficulty is experienced in obtaining sharp and perfect castings owing to the sluggishness of the metal and the necessarily comparatively small mass of molten 15 metal.

My present invention, which is the basis 20 of the apparatus described and claimed in my pending application Serial Number 381,416, relates to a machine by means of which castings of the character described 25 may be easily and perfectly made. To this end I provide a mold and immediately adjacent crucible in which gold and other similar metal may be melted, and means by which the mold and molten metal in the crucible may be suddenly moved, after the melting has been accomplished, so as to cause the metal to flow into the mold.

30 The accompanying drawings illustrate an embodiment of my invention in a machine especially designed for use by dentists although by no means limited to such use.

Figure 1 is a front elevation with the machine arranged to operate in a vertical plane; Fig. 2 a side elevation; Fig. 3 a section on line 3—3 of Fig. 1 and the main body of the machine arranged as it would be for operation in a horizontal plane; Fig. 40 4 a section in line 4—4 of Fig. 3, and Figs. 5 and 6 details of the mold and adjacent crucible.

In the drawings 10 indicates a mold which may be conveniently made by investing 45 the pattern in a hardening plastic and then burning or melting the pattern so as to leave the hollow or receptacle 11, access being given thereto through the usual contracted sprue or gate passage 12. The mold 50 10 may be conveniently formed in a holder 12 adapted to be readily slipped into or out of a crucible holder or arm 14 which carries a crucible 15 having a basin or cup and an outlet passage 16 which leads directly to

the outer, or receiving, end of the gate passage 12. The crucible 15 must be of some refractory material and should be so formed, as indicated in the drawings, that in it may be melted—blow-pipe heat or otherwise—a sufficient quantity of metal, such as gold, to fill the mold. Arm 14 is carried by a rotatable shaft 17 mounted in a suitable case 18 and secured to said shaft is one end of a spring 19 the other end of which is secured to the case. A suitable brake or 65 catch 20 operating against a balance wheel 21 is provided to normally prevent the rotation of the shaft by the spring. Of course any other motor may be used to drive the shaft but such motor should be of such character that the mold and molten metal may be moved suddenly at a comparatively high speed so that the molten metal will be caused to flow into all parts of the mold 70 while it is still hot enough to be fluid. 75

If desired, arm 14 may carry a mold and crucible at each end at opposite sides of the axis of revolution and by such an arrangement two operators may use the apparatus simultaneously if it is arranged to operate 80 in a horizontal plane.

The case 18 incloses the arm 14 so as to form a chamber 22 in which any flying portions of metal will be caught and saved.

In order to adapt the device for use in 85 either a horizontal or a vertical plane I have provided it with two bases 23 and 24 as shown and arm 14 is provided at each end with a fork 25, into which the mold-cup may be slipped, and a flange or lip 26 which— 90 with the fork—forms a crucible-retainer into which the crucible may be put either in a plane at right angles to the axis of revolution or in a plane parallel therewith, as shown in Figs. 5 and 6. 95

In operation;—the mold and its crucible are associated in the manner shown in the drawings and the spring wound up. Gold or other metal is placed in the crucible, mold and metal heated, by blow-pipe or otherwise, 100 until the gold is melted. Shaft 17 is then released and immediately put into rapid motion so that the molten metal is driven by centrifugal force into all parts of the hollow of the mold so as to sharply fill the same. 105

I am aware of Patent No. 510,999 issued December 19, 1893 to J. L. Lebenius and disclaim the structure therein shown. In that

device the part *a* is merely a sprue or passage to the molds and must necessarily be substantially at the center of rotation and must be annular in form in order that a continuous stream of molten metal can be poured into the same. Its capacity must also be considerably less than the mold or molds to which it delivers.

I claim as my invention:—

10 1. A casting apparatus, comprising a rotatable arm, a mold supported on said arm at a point distant from its axis, and a melting crucible also carried by said arm adjacent the mold between the mold and the axis of revolution and arranged to discharge into the mold.

15 2. A casting apparatus, comprising a mold, means for revolving said mold about an external axis, and a melting crucible arranged between the mouth of said mold and the axis of revolution and so as to discharge into the mold.

20 3. A casting apparatus, comprising a mold having a contracted entrance, a melting crucible arranged at the mouth of said entrance to discharge thereto, and means for revolving said crucible and mold about an axis external to the mold to cause the molten metal to flow by centrifugal force into the mold.

25 4. A casting apparatus, comprising a mold, a melting crucible having a capacity at least equal to the mold arranged adjacent the mouth of said mold to discharge therefrom, and means for revolving said mold and crucible around an axis external to the mold to cause the metal to flow by centrifugal force into the mold.

30 5. A casting apparatus, comprising a mold, a melting crucible having a capacity at least equal to the mold arranged adjacent the mouth of said mold to discharge thereto, means for revolving said mold and crucible suddenly around an axis external to the mold to cause the metal to flow by centrifugal force into the mold, and means for normally restraining such movement.

35 6. A casting apparatus, comprising a mold, a melting crucible having a capacity at least equal to the mold arranged to deliver thereto, and means for moving the mold and crucible in such direction as to cause the molten metal in the crucible to flow by centrifugal force into the mold.

40 7. A casting apparatus, comprising a mold, a melting crucible having a capacity at least equal to the mold arranged to deliver thereto, means for suddenly moving the mold and crucible in such direction as to cause the molten metal in the crucible to flow by centrifugal force into the mold, and means for normally restraining such movement.

45 8. A casting apparatus, comprising an arm, means by which said arm may be

swung, a melting crucible carried by said arm near its outer end and a mold also carried by the arm beyond the crucible in position to receive molten metal therefrom by centrifugal force.

70 9. A casting apparatus, comprising a main case, a shaft journaled in said case, a motor for driving said shaft, means for controlling the motor, a radially extending arm carried by the shaft, a mold carried at the outer end of the arm, and a melting crucible also carried by the arm near its outer end in position to deliver to the mold.

75 10. A casting apparatus, comprising a main case, having two bases adapted to support the case in either of two positions substantially at right angles to each other, a shaft journaled in said case, a motor for driving said shaft, means for controlling the motor, a radially extending arm carried by the shaft, a mold carried at the outer end of the arm, and a melting crucible also carried by the arm near its outer end in position to deliver to the mold.

80 11. A casting apparatus, comprising a main case, a shaft journaled in said case, a motor for driving said shaft, means for controlling the motor, a radially extending arm carried by the shaft, a mold carried at the outer end of the arm, and a melting crucible also carried by the arm near its outer end in position to deliver to the mold.

85 12. A casting apparatus, comprising a main case, having two bases adapted to support the case in either of two positions substantially at right angles to each other, a shaft journaled in said case, a motor for driving said shaft, means for controlling the motor, a radially extending arm carried by the shaft, a mold carried at the outer end of the arm, and a melting crucible also carried by the arm near its outer end in position to deliver to the mold, a portion of the case forming a chamber within which are arranged the arm and the parts carried thereby.

90 13. A machine of the class described, comprising a standard, a spring actuated arm arranged for rotation thereon, means whereby a flask is detachably positioned on the arm, and a metal holding plate detachably arranged on the arm in front of the flask holding means.

95 14. A machine of the class described comprising a vertically disposed revoluble body, a melting tray carried by said body, and a flask carried by the melting tray and arranged to receive therefrom molten metal impelled by centrifugal force.

100 15. A molding machine having a flask, a crucible for molten metal operatively assembled in relation to the flask, and means

for overturning the flask and crucible to forcefully throw the molten metal outwardly from the crucible into the flask.

16. A molding machine having a flask and a crucible containing molten metal and assembled in co-operative relation to the flask and having one extremity engaging the latter, and means for overturning the flask and crucible to forcefully throw the molten metal from the crucible into the flask.

17. In a molding machine, a flask, a crucible engaging the flask and having one extremity removably fitted in the latter, and means for overthrowing the flask and crucible to force the molten contents of the crucible into the flask.

18. In a molding machine, a flask, a crucible engaging the flask, and overthrowing rotary means to which the crucible and flask are connected and operating the latter to forcefully throw the molten contents of the crucible into the flask.

19. In a molding machine, a rotary shaft having an overthrowing arm, a flask and crucible removably held by the arm, and means for rotating the shaft.

20. In a molding machine, a rotary shaft, a flask and crucible connected to the shaft, the flask and crucible being overturned by the shaft, means for holding the shaft in immovable position, and means for rotating the shaft when the latter is released.

21. In a molding machine, a rotary shaft having a flask and crucible connected thereto, the flask and crucible having an overthrowing operation in relation to the shaft, means for holding the shaft against movement, and means for turning the shaft when released.

22. In a molding machine, a rotary shaft, a flask support connected to the shaft, a flask removably mounted in the support, and a crucible having one extremity operatively engaging one end of the flask, the flask support, flask and crucible having an overthrowing movement imparted thereto by the shaft.

23. In a molding machine, a flask support, a flask removably mounted in the support, and a crucible operatively engaging one extremity of the flask, the flask support, flask and crucible having an overthrowing movement imparted thereto.

24. In a molding machine, a rotary shaft, a flask and crucible connected to the shaft, means for holding the shaft in immovable position, and means for rotating the shaft when the latter is released.

25. A machine for casting dental inlays or other articles, comprising a bar mounted to rotate in a vertical plane, a mold-holder mounted at each extremity of the bar, a mold removably connected therewith, a pan mounted on the bar in front of the mold, a

spring for rotating the bar and a ratchet 65 and pawl constructed for locking the bar in the desired position of adjustment, substantially as described.

26. A machine for casting dental inlays or other articles, comprising a bar mounted 70 to rotate in a vertical plane, and equipped at each extremity with a mold-holder and a mold removably connected therewith, a pan mounted in front of each mold-holder, a spring normally detached from the bar, 75 means for connecting the spring and bar, whereby the spring may be placed under tension by rotating the bar in a given direction, means for locking the bar in the adjusted position with the spring under tension, the said means being adapted to release the bar and allow it to rotate in response to the recoil of the spring, substantially as described.

27. A machine of the class described, comprising a spring-actuated-bar mounted to rotate in a vertical plane, and having means mounted at each extremity thereof for casting dental inlays or other articles, and a pan located in front of each mold, and in 90 position to allow the molten metal placed therein to be driven into the mold by the centrifugal force developed by the rotation of the bar, substantially as described.

28. The combination with a suitable 95 frame, of a spindle journaled in the frame, a bar fast on the spindle, and having a mold-holder at each extremity, a mold removably connected with the holder, a pan mounted in front of each mold, a spring mounted on 100 the spindle, and a suitable connection between the spring and the bar, whereby when the latter is rotated in one direction the spring is placed under tension, the spring serving to rotate the bar in the opposite direction when the latter is released, whereby the centrifugal force is developed for carrying molten metal from the pan into the molds of the bar, substantially as described.

29. A machine of the class described, comprising a bar mounted to rotate in a vertical plane, a mold-holder mounted at each extremity of the bar, a mold removably connected with the holder, a pan removably connected with the bar and located in front 115 of each mold, and means connected with the bar for rotating the same to develop the necessary centrifugal force to carry molten metal from the pans into the molds, substantially as described.

In witnesss whereof, I, have hereunto set my hand and seal at Indianapolis, Indiana, this second day of March, A. D., one thousand nine hundred and eight.

ALEXANDER JAMESON. [L. S.]
